US00D985785S

(12) **United States Design Patent** (10) **Patent No.:** **US D985,785 S**
(45) **Date of Patent:** **** May 9, 2023**

(54) **HAND WARMER**

(71) Applicant: **Shenzhen Senyuesheng Technology Co., Ltd.**, Shenzhen (CN)
(72) Inventor: **Meifang Xiao**, Shenzhen (CN)
(73) Assignee: **SHENZHEN SENYUESHENG TECHNOLOGY CO., LTD.**, Shenzhen (CN)

(**) Term: **15 Years**

(21) Appl. No.: **29/808,642**

(22) Filed: **Sep. 22, 2021**

(51) **LOC (14) Cl.** **24-01**
(52) **U.S. Cl.**
USPC **D24/206**

CLAIM

The ornamental design for a hand warmer, as shown and described.

DESCRIPTION

FIG. 1 is a perspective view of a hand warmer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the hand warmer that form no part of the claimed design.

1 Claim, 8 Drawing Sheets
